UNITED STATES PATENT OFFICE

2,448,648

SOLAR WATER HEATER

Ernest E. Zideck, Pontiac, Mich., assignor of one-half to Clinton L. Stockstill, Wayne County, Mich.

Application September 8, 1944, Serial No. 553,259

2 Claims. (Cl. 257—256)

1

This invention relates to new and useful improvements in water heaters such as are employed in localities where the sun rays can be employed as a heating medium.

The principal object of the present invention is to provide a solar water heater which will be more practical than those now in general use due to the manner in which the heater elements exposed to the rays of the sun are contained in a multiplicity of individual units which may be arranged side by side or one above the other and connected individually to water inlet and water outlet pipes, with a view toward offering facilities of installation of as many units as may be required for the heater area in each given instance.

Another important object of the invention is to provide a solar water heater wherein the heater area exposed to the rays of the sun is composed of individual units in each of which the various heating elements are sturdily secured and wherein the rise of hot water above the cold water through the so provided water channels cannot be impaired by a sagging roof or through other causes.

Various other important objects and advantages of the invention will become apparent to the reader of the following description.

In the drawings:

Figure 1 is a side elevational view with a portion broken away showing a heat exchange unit according to the invention.

Figure 2 is a longitudinal sectional view taken substantially on line 2—2 of Figure 4.

Referring now to the drawings, the numeral 19 designates an embossed plate-like member which may be formed as a casting or by a die-stamping process or in any other suitable manner. This member 19, as shown, is formed with thickened upper and lower apertured and internally threaded bosses or burrs 20, 21, to receive the threaded ends of outlet and inlet pipes (not shown). The member 19 is formed to provide a vertically extending medial depression or passageway 22, laterally from which horizontally disposed V-shaped channels 23 are formed. These V-shaped channels define tapered islands 24 and tapered peninsulas 25. Spaced from and interposed between opposed peninsulas 25 and within the middle passageway 22 are circular islands 26.

On the outer side of the member 19, contiguous to and concentric with each circular island 26, is formed a cavity which actually opens with very small aperture through the central portion of the island 26 and this is so that in addition to weld-

2

ing the edge portion of a cover plate 27 over the member 19, the plate 27 is thus further reinforced tied to the member 19 by welding material applied through these openings, the cavities being denoted by the reference numeral 28 and the welded spots by the numeral 29.

As can be seen in Figure 1, the lower sides of the lowermost V-shaped channels 23 slope downwardly to the cold water inlet boss or burr 21. Further, the upper sides of the uppermost V-shaped channels 23 slope upwardly to the hot water outlet boss or burr 20, while the intermediate channels 23 slope alternately downwardly and upwardly into communication with the vertical medial passageway 22. Thus, it can be seen that at all points in the water passageways there is a gradual and continuous rise as the water becomes heated in the device.

The upper and lower ends of the units shown in Figures 1 and 2 may have longitudinally extending conduit connections in addition to the boss or burrs 20, 21 and if the longitudinally extending connections are employed, then the parts 20, 21 are plugged. It would be advisable to have these two sets of connections because of the possibility that conditions might require the use of one or the other in mounting the apparatus.

Several of the units shown in Figures 1 and 2 may be associated in a parallel or series cooperative association in use.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. A solar water heater unit comprising a plate-like member having an inner surface provided with a depressed channel formation therein, said channel formation comprising a vertically extending medial passageway extending from end to end of the unit and horizontally disposed V-shaped channels projecting laterally from opposite sides of said medial passageway and extending from end to end of the unit, the channels at intervals throughout the length thereof communicating directly with said medial passageway, tapered islands formed coincidentally within and defining some of the wall portions of said channels with intervening alternate pointed peninsulas defining the opposite wall portions of said channels, said islands and said peninsulas together defining a multiplicity of communicable

openings between said channels and said medial passageway, circular islands formed within said medial passageway at the communicable openings of the channels with said medial passageway, a complementary plate-like covering member attached to said first-mentioned plate-like member and at intervals throughout the area thereof to said circular islands, water inlet means provided at one end of the unit communicable with the adjacent ends of the channels and the adjacent communicable end portion of the medial passageway, and water outlet means provided at the opposite end of the unit and communicable with the adjacent portions of said channels and the adjacent end portion of said medial passageway.

2. A solar water heater unit comprising a plate-like member having a vertically extending medial passageway formed on its inner surface and extending from its lower end to its upper end; and horizontally disposed V-shaped channels projecting laterally from opposite sides of said medial passageway and extending from the lower end to the upper end of the unit, said channels communicating with said medial passageway at intervals throughout the length of the latter, a second plate-like member covering said first-mentioned plate-like member and the channels thereof, there being provided a water outlet at the upper portion of the first-mentioned plate-like member in communication with the adjacent uppermost portions of the medial passageway and the communicating channels, a water inlet at the lowermost portion of said first-mentioned plate-like member in communication with the adjacent lower end portions of said medial passageway and channels of the member, said second-mentioned plate-like member being secured water-tight to said first-mentioned plate-like member, said first-mentioned plate-like member being provided with

5 a multiplicity of cavities on its outer surface with central relatively small apertures extending centrally through circular islands on the inner surface thereof and located at the respective communicating intervals of the channels with the medial passageway, and attaching means applied through the central openings of said cavities of the first-mentioned plate-like member and secured to the adjoining portions of the second-mentioned plate-like member to provide a multiplicity of spot attachments of the second-mentioned plate-like member to the first-mentioned plate-like member and affording a material strengthening and reinforcing attachment between the first and second-mentioned plate-like members.

ERNEST E. ZIDECK.
